Primary Examiner — Jae Liang(74) *Attorney, Agent, or Firm* — Dickinson Wright,
PLLC; Michael E. Noe, Jr.**CLAIM**

The ornamental design for a beverage container, as shown and described.

DESCRIPTION

FIG. 1 is a perspective view of a beverage container;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines in the drawings depict portions of the beverage container that form no part of the claimed design.
